UNITED STATES PATENT OFFICE.

DONALD S. BARROWS, OF ROCHESTER, NEW YORK.

WIND BUNG FOR MELTING FURNACES.

1,416,439.

Specification of Letters Patent. Patented May 16, 1922.

Application filed March 17, 1920. Serial No. 369,563.

To all whom it may concern:

Be it known that I, DONALD S. BARROWS, a citizen of the United States, residing at Rochester, in the county of Monroe and 5 State of New York, have invented certain new and useful Improvements in Wind Bungs for Melting Furnaces; and I do hereby declare the following to be a full, clear, and exact description of the invention, such 10 as will enable others skilled in the art to which it appertains to make and use the same.

The invention, broadly stated, relates to furnaces and more particularly to improvements in the construction of one or more of 15 the removable roof members used in that type of furnace which is adapted to re-melt pig iron with steel, cast iron or malleable iron scrap, the re-melted metal being used in 20 the production of grey or malleable iron castings.

The principal object of my invention is to provide an air supplying roof member or wind bung for use in connection with the 25 type of furnace set forth above, said member preferably comprising metallic side members, a metallic closure or top member, and heat resisting lining members, the latter being arranged to provide openings to permit 30 the escape of air from the member or bung.

Another object of my invention is to provide a removable roof member for melting furnaces having a plurality of spaced metal 35 frame members each of which is provided at opposite ends with clamping means for holding the heat-resisting lining members or bricks in assembled position.

Still another object of the invention is to 40 provide a removable roof member or bung having a pair of spaced side members each of which is provided with upper and lower flanges, the said upper flanges affording means for connecting a metallic cover plate 45 thereto, the said lower flanges affording a wide bearing area for the lining members or bricks.

A still further object of the invention is to 50 arrange the heat resisting lining members of a furnace bung so that there is provided a series of openings therethrough to permit the escape of air from the said bung.

Other objects of the invention will appear from the more detailed description of the

same when taken in connection with the accompanying drawing, in which,—

Figure 1 is a top plan view, partially in section of a portion of a wind bung constructed in accordance with my invention. 60

Fig. 2 is a side elevation of the structure illustrated in Fig. 1.

Fig. 3 is a side elevation of the opposite end of the wind bung from that shown in Fig. 2; and

Fig. 4 is a transverse section taken on line 4—4 of Fig. 2.

Throughout the specification and drawings like parts are designated by like reference characters.

The numeral 1 designates the roof member or bung which preferably comprises a plurality of flanged side members 2, 2, which may be formed from any commercially rolled members and which are here shown as I-beams. To the outer ends of each of the I-beams 2 is connected an adjusting clamping device 3, illustrated and described in my co-pending application Serial No. 313,986, filed July 29, 1919. These clamping devices are 80 preferably employed at each end of each beam, and are adapted to hold the lining bricks 4 in close contact with the lower flanges 5 of the I-beams 2, 2. Each clamping device is provided with a pivoted shoe 85 6 adapted to engage the face of the outermost brick 4. The clamping members through the instrumentality of the pivoted shoes 6 transmit the pressure from each clamp through the center line of the lining 90 bricks practically parallel to the face of the lower flange 5 of the I-beams 2 and hence the lining bricks are securely clamped to the frame members without any tendency to separate at either their upper or lower 95 portions, as is fully described in the application above set forth.

The top flanges 7 of the said I-beams are preferably united by means of a plate 8 which extends transversely from flange to 100 flange and is firmly connected thereto, as for example, by rivets 9. At one end of the bung frame adjacent the end of the plate 8 there is provided a baffle or closure plate 10 which extends from the cover plate to the 105 lining bricks 4. At the opposite end of the bung frame the plate 8 preferably terminates at a distance from the end of the members 2, and interposed between the end of the plate 8

and the baffle plate 12 is the inlet pipe 13 hereinafter more fully described. The said inlet pipe 13 is provided with a base member 11 adapted to fit the upper surface of the I-beams 2 and to thus form in effect a continuation of the plate 8. It will thus be seen that the bung frame comprises the side members 2, the top member 8, the baffle plates 10 and 12 and the base member 11 of the inlet pipe 13, and that these members are so connected and arranged as to form a box or hollow frame closed on three sides and at either end.

The bricks 4^a which line the open face of the bung frame between the closure or baffle plates 10 and 12 are not continuous as are the bricks 4, but are of two sizes and are of such length that two of these bricks of uneven length when placed end to end must be separated a slight amount or spaced apart in order that the ends of the bricks will extend to the outer ends of the lower flanges of the members 2. The arrangement of these bricks is clearly shown in Figs. 1 and 2. The space between each pair of bricks of unequal length provides outlet openings 14 extending from the hollow box or frame member, and these openings 14 are in staggered relation, as clearly shown in Figs. 1 and 4. By employing bricks which are comparatively narrow in width I obtain by this staggered relation the effect of two continuous wind slots extending the full length of the bung between the baffle plates, and at the same time avoid the necessity for using and forming special bricks or for cutting holes through the ordinary form of bricks.

The wind bung is provided with a clevis or ring bolt 15 to engage the hook of the derrick member to permit the removal or replacement of the bung on the furnace wall.

It will be noted that adjacent the inlet

pipe 13 the inwardly extending portions of the top flanges 7 of the beams 2 are cut away as shown at 16 so as not to limit the opening from the pipe 13.

Having now fully described my invention, what I claim and desire to secure by Letters Patent is:—

1. In a furnace bung, the combination with 50 a plurality of flanged members, of means for connecting said members to form a chamber therebetween, a lining of fire-resisting material engaging said flanged members, means for holding said lining in position, means 55 for admitting air to said chamber, and a plurality of staggered slots in said lining member to permit the escape of air from said chamber.

2. In a furnace bung, the combination with 60 the frame member, of lining members comprising a plurality of alternately arranged pairs of fire bricks, the adjacent ends of each pair of bricks being spaced apart to provide openings extending through said 65 lining members, and means for connecting the said frame members to form a chamber therebetween, and means for admitting air to said chamber.

3. In a furnace bung, the combination with 70 longitudinally extending frame members, of means for connecting said frame members intermediate the ends thereof to form therewith a hollow chamber, and lining bricks closing the under side of said chamber, said 75 bricks being of different lengths and being arranged in alternate pairs, the adjacent ends of each pair being spaced apart to form an outlet from said chamber, means for admitting air to said chamber, and means for 80 maintaining said lining members in position.

In testimony whereof I affix my signature.

DONALD S. BARROWS.
